STILLWELL W. McMICHAEL, OF FULLERTON, CALIFORNIA.

SWIMMING APPLIANCE.

1,277,022.

Specification of Letters Patent. Patented Aug. 27, 1918.

Application filed March 22, 1918. Serial No. 224,022.

To all whom it may concern:

Be it known that I, PORUS J. YOUNG, a citizen of the United States, residing at Santa Susana, in the county of Ventura and State of California, have invented certain new and useful Improvements in Swimming Appliances, of which the following is a specification.

The present invention is a device for use 10 by a swimmer who is partly supported by the float and provided with means for propelling himself or herself through the water, and the object of the same is to produce such a device which is extremely simple and 15 light, easy of application, and readily understood and operated by anyone without previous experience.

This and other objects are accomplished by constructing the device in the manner 20 hereinafter more fully described and claimed, and as shown in the drawings, wherein:

Figure 1 is a plan view of this swimming appliance complete,

25 Fig. 2 is a side elevation of the same showing how it is applied to the human figure,

Fig. 3 is an enlarged sectional detail on the line 3—3 of Fig. 1.

In the drawings the numeral 1 designates 30 a float which may be a piece of board or the like, or a flat element made buoyant in any suitable way as by being of metal and made hollow, and 2, 2 are shoulder straps or hooks secured to the front end of the float as

35 shown, while 3, 3 are straps secured at 4 to the edges of the float at its rear end and adapted to be drawn across the back and buckled as at 5. If desired, the float may be provided with a pneumatic pad 6, made

40 preferably in the shape of the letter U as indicated and preferably secured upon the float by means of straps 7 or other fastening devices, and when inflated this pad not only sustains the weight of the user but presents

45 a rather soft cushion between his or her body and the upper face of the float itself. The pad may be blown up by suitable means, such as the nipple N, and the pad may be of some light and soft material so long as the 50 general idea is carried out.

The numeral 11 designates an extension which is not so wide as the float, and whose forward end extends into a slot 10 at the rear of the float and is pivotally mounted 55 therein on a transverse bolt 12. As seen in

Fig. 3, the forward extremity of the extension is preferably provided with a reduced tongue 13 which extends loosely between top and bottom plates 14 that are carried upon the upper and lower faces of the float 1 as 60 seen in Fig. 1. Above and below the reduced end or tongue 13 are washers 15 of rubber, and finally an upright bolt 16 passes through both plates 14, all washers 15, and the tongue 13, and preferably has a wing nut 65 17 at its lower end by means of which it can be removed and replaced when desired. Thus the angle of the extension 11 to the float 1 can be adjusted by removing this bolt and re-arranging the washers 15. In Fig. 3 70 one of these washers is shown above and three beneath the tongue 13, so that the general position of the extension 11 is one of inclination downward, as will be seen. Different operators or users may desire the angle of the two main parts adjusted, and this detail permits such adjustment, while at the same time it permits a certain amount of flexibility because the washers 15 will probably be of soft rubber.

Disposed within a slot 20 near the rear end of the extension 11 is an upright power gear 21, mounted on a crank shaft 22 having pedals 23 at its extremities. In mesh with the driving gear 21 is a bevel pinion 24 at the 85 forward end of a driven shaft 25 mounted in suitable bearings 26 beneath the extension 11 and carrying at its rear end a propeller 27; and 28 is a wire guard inclosing this propeller so that the operator may not 90 injure himself thereon and so that the propeller may not drag on the bottom when the water is shallow.

The operation is quite obvious from Fig. 2. The float being strapped upon the chest 95 and stomach of the user, the extension projects between the limbs and is preferably made narrow so as not to interfere with their movement. The proper adjustment of the extension 11 to the float 1 is attained by 100 the position of the washer 15 as above suggested. Now the user puts his feet on the pedals 23, and by revolving the driving wheel in the proper direction the propeller 27 is caused to rotate rapidly within the 105 water, leaving the operator meanwhile at liberty to use his or her arms to assist the propelling and perhaps to learn swimming. With the beginner, the pad 6 may be used and inflated to a considerable extent, and 110

from time to time the air may be let out of this pad so that eventually the operator is assisted only by the float, and then the pad can be entirely removed. In this way swimming can be taught, and in rough waters the device will be useful to those who know how to swim. The parts may be made in sizes for adults and children, but usually I find that the float 1 will constitute a body portion which may be made in standard sizes and an extension 11 of proper length may be fitted thereto according to the height of the operator or user. Otherwise the details of parts are hardly essential.

15. What is claimed as new is:—

1. In a swimming appliance, the combination with a body-float having a notch in its lower end, a narrow extension whose upper end projects into said notch and whose extremity is formed into a reduced tongue, and propelling mechanism at the lower portion of said extension; of a pivotal connection between the extension and float near the lower end of the latter, plates secured to the 25 opposite faces of said float in line with said

tongue, a bolt through the plates and tongue, and a series of washers strung on said bolt above and below the tongue and selectively disposed to alter the angle of the extension to the float.

2. In a swimming appliance the combination with a body-element forked at its lower end, a narrower element extending into said fork and pivoted between the fork-arms near their lower extremities, and propelling mechanism carried by the lower portion of said narrower element; of plates carried by the body element above and below the upper extremities of said extension element, and compressible members selectively disposed above and below said extremity for adjusting the angle of the two elements to each other, for the purpose set forth.

In testimony whereof I affix my signature in presence of two witnesses.

PORUS J. YOUNG.
